William B. Zerr,

By his Attorney
Thomas P. Kinsey

UNITED STATES PATENT OFFICE.

WILLIAM B. ZERR, OF SPRING, BERKS COUNTY, PENNSYLVANIA.

DEVICE FOR CLEANING WINDOWS.

SPECIFICATION forming part of Letters Patent No. 396,133, dated January 15, 1889.

Application filed March 29, 1887. Serial No. 232,834. (Model.)

To all whom it may concern:

Be it known that I, WILLIAM B. ZERR, a citizen of the United States, residing in Spring township, county of Berks, State of Pennsylvania, have invented a new and useful Improvement in Devices for Cleaning Windows, of which the following is a specification.

This improvement pertains more particularly to the class of window-washers intended to be secured with the rubber in proximity with the glass upon the outside of the window and to be operated from the room on the inside of the window.

The object of the invention is to improve this class of devices and make their operation thoroughly effective.

The drawings accompanying this specification and forming part of the same show very clearly the nature and use of my improvement, like letters of reference indicating like parts throughout—

Figure 1 representing the device in full side elevation, with a portion of a window frame and sash in sectional elevation; Fig. 2, a rear or inner elevation of the same; Fig. 3, a front end elevation of the device; Fig. 4, a plan looking down upon the same; Fig. 5, representing in side elevation the device with an attachment whereby it is adapted to be used for cleansing windows of an unusual height; Fig. 6, an inner end view of the same, showing the continuation of the guides, whereby the movement of the rubber is made continuous; Fig. 7, detailed front and side elevations of the cross-head, showing therewith the clamping device for the washing-rubber; Fig. 8, a plan and side elevation of the clamping device detached from the cross-head; Fig. 9, a front and side elevation of the post adjustment; Fig. 10, a front and side elevation of the compensating spring-balance for the cross-head.

In the drawings, A represents the base; B, a standard at the outer end of the base; C, a clamping-screw adapted to slide in a slot, A', at the inner end of the base and engaging a clamp, C', formed with a projecting lug, C², to catch under the window-sill upon the inside of the room, and a guide-pin, C³, to keep the body at right angles with the slot.

The vertical post D is pivoted at D' to the

standard B, and is provided at its lower end with a centrally-secured eye-piece, E, having a set-screw, E', the eye bored to pass freely over a curved guide, F, struck by a radius 55 from the pivot D' to the center of the same, said guide having legs F' and feet F² by which it is secured to the base.

Guides G extend from near the base to within a short distance of the top of the post 60 D, said post being centrally recessed at D² to permit the cross-head P to traverse the post, said guides G lapping over the sides of the recess. Stops H are placed at the top and bottom of the post within this recess, which 65 limits the movement of the cross-head in both vertical directions.

A pulley-mortise, D³, is placed central to the post just at the lower stop H, and has inserted therein an ordinary cord-guide pulley, I, one 70 of the same kind, I', being secured to the side and near the lower end of the post D, a pillar guide-pulley, I², being secured central to and in the extreme upper end of the post. On the front face a standard, J, is secured 75 upon the edge of the post D and near its upper end, and supports removably a case, K, containing a spiral flat spring, K', said spring secured at its inner end upon the non-revolving stud L and at its outer end to the periphery of the case, said case adapted to revolve 80 upon said stud, which is secured in said standard by a nut, L'.

A cord, M, passes from the top of the cross-head P to the pillar-pulley I² and downward 85 to pulley I'; then in toward the rear of the base, terminating in a handle, M'. A cord, N, also passes from the lower end of the cross-head to and under the pulley I; then upward to the case K of the compensating spring-balance, is wrapped several times around the periphery of the same, and secured in place.

A metallic cross-head, P, is made of sufficient length vertically to give it steadiness. The edges P' are grooved to slide freely over 95 the guides G. A bracket, P², projects inward from the cross-head P, and is provided with a clamping-screw, Q, adapted to clamp the window-glass rubber R to the cross-head. An eye, P³, at the top serves as a point of attachment for the cord M, and an ear, P⁴, with a suspended eye at the lower end, for the attach-

ment of the cord N. The clamp is composed of two pieces, S S', which are made at their free ends to conform to the shape of the rubber R, the inner end of the lower clamp, S', 5 being cut off to clear the brace and threaded to fit the clamping-screw Q, the upper clamp, S, being extended beyond the clamping-screw and terminating in a fan-shaped tail, S², having a slot, S³, struck from the center of the 10 clamping-screw, the slot occupying a little more than a semicircle. A pin, S⁴, permanently secured in the top of the brace, fits freely in the slot S³, and the head of the pin retains the clamp in movable contact with the brace. This arrangement permits of the swiveling around of the rubber and its adjustment to bay-windows and corners of ordinary ones, where the rubber could not reach if rigidly fixed at right angles with the post.

15 For the purpose of adapting the device to windows of considerable difference in height I provide an extra detachable post, D⁴, having an enlarged base bifurcated at D⁵, adapted to be set into the pockets T' of the casting T, secured to the top of the post D. As the pressure of operating is altogether downward, there is no other fastening required. The post D⁴ is provided with a continuation of the guides G, has a pillar-pulley, I², permanently secured to its top, and a standard, J', permanently attached to one of its edges and bored to receive the stud L of the case K.

20 To make use of the attachment, the pillar-pulley I² is removed from the post D and the compensating-spring case is removed from the standard J and transferred to the standard J'. The post D⁴ is then connected with the post D by having its bifurcated legs D⁵ set in the pockets T', as described.

25 The use of the device is as follows: The sash is raised, so as to permit the machine to be placed in position, the base-board being set upon the sill of the window, the upper sash drawn down, and the post drawn in toward the sash until the rubber rests against the glass, in which position the base-board is clamped to the window-sill, a block of the proper height being interposed between the base and sill to make the clamp effective. As

30 an additional precaution to give security to the base hooks U may be connected with the base at the sides, adapted to catch under the sill outside of the window. These hooks are made adjustable by a movable right and left hand thread nut, U'. Having secured the 35 base in position, the post D is adjusted on its pivot D' by the set-screw E' and eye E and guide F. The sashes are then adjusted relative to the sweep of the rubber, and operation may commence. The handle M' is grasped and drawn toward the operator, when the rubber will rise and the compensating spring-balance K' will be wound up. On releasing the 40 pull the spring will draw down the rubber and the cord M will rewrap itself upon the barrel for a repetition of the movement.

Having shown the application and described the use of my invention, I desire to claim as follows:

1. In a window-cleaning device, the combination, with a base-piece having a standard at its outer end, of a post adjustably pivoted to said standard, a cross-head located in guides in the post, a rubber attached to the cross-head, an operating-cord secured to the top of said cross-head, and a separate cord secured to the bottom and attached to a spring-balance, all arranged and adapted to operate substantially as set forth. 75

2. In a window-cleaning device, the combination, with a cross-head guided in a vertical post secured to a base-piece, of two cords attached to opposite sides of said cross-head, one of which is adapted to raise said cross-head and the other is connected to a spring-balance and adapted to lower it, substantially as set forth. 80

3. In a window-cleaning device, the combination, with a vertical post provided with guideways, of a cross-head adapted to move in said guideways, and having a clamp for a suitable rubber pivoted horizontally to it, substantially as set forth. 85

WM. B. ZERR.
